MEANS FOR SUPPLYING OIL TO A
SPINNING RING

Andrew J. Wayson, Needham, Mass., assignor to Merriman Bros., Inc., Boston, Mass., a corporation of Massachusetts

Filed June 15, 1960, Ser. No. 36,379
5 Claims. (Cl. 57—120)

This invention relates to the textile industry and is particularly concerned with the provision of new and novel means for supplying oil to a spinning ring. When the term spinning ring is used herein, it will also be understood to encompass the term twisting ring. When the term oil is used herein, it is understood that reference is made to any liquid medium that can serve as a lubricant for the traveler of the spinning ring.

In the spinning of textile yarns, spinning rings made of powdered metal have come into extensive use. Powdered metal rings are of a porous nature so that oil fed to such rings permeates the entire ring to produce a very thin film of oil over the entire working surface. This oil film is adequate to properly lubricate the traveler as it moves at high velocity about the ring.

In supplying oil to powdered metal rings, one of the major problems has been to supply the oil in the right quantity. If oil is supplied at too great a rate, a surplus will accumulate on the ring and drip therefrom, with the possibility of spoiling or damaging the yarn. If the oil supplied is too little, then the lubrication will be inadequate and the travelers will wear out too quickly. A solution to the problem of supplying oil to powdered metal rings at the proper rate has been achieved through the utilization of metering means in the form of felts of varying absorptive capacities. These felts are supplied with oil by wicks from a main oil reservoir and the oil in the felts is then transferred to wicks which lead into one or more circumferential grooves about the spinning ring. Thus oil can be transferred from the felt to the ring only as fast as the felt receives oil from the main oil reservoir by means of the wick leading from the reservoir to the felt. By using felts of greater or less oil absorbing capacity, the rate of oil fed to the ring may be controlled.

According to the practices of the prior art in this particular field, it has been necessary to periodically replenish the oil supply in each individual reservoir of each spinning ring. While the reservoir is generally of sufficient capacity to maintain the oil supply to the ring for a substantial period, nevertheless replenishing of the oil supply must be done regularly; and in a textile mill, where literally thousands of rings are in operation, the labor cost for this work is substantial.

Means for supplying oil to the individual rings of a spinning frame from a common central supply has long been known in the art, but up to the present this method of lubrication has only been used with solid non-porous steel spinning rings. By means of periodic pumping impulses, small quantities of oil have been supplied to the interior areas of such solid rings with limited success, but such process is not capable of adaptation to use with porous rings because the oil fed to the porous ring must be fed slowly and continuously, for the oil must be absorbed by the ring to pass slowly therethrough. Periodic applications of oil to a porous ring does not give satisfactory results.

According to the present invention, it is proposed that a central source of oil be provided with feed pipes running to the individual reservoirs that are associated with each of the powdered metal spinning rings mounted on the ring rail of a spinning frame. The oil reservoir will be either continuously supplied or periodically refilled with oil pumped thereto from the central source. Re-

2

gardless of the oil level in the reservoir, the oil will be transferred by means of a suitable wick to the metering felts which reside in a separate compartment. The oil by capillary attraction travels through the felts in a known manner to be transferred to a second wick which runs from the felts to the grooves surrounding the powdered metal rings. In this way, the rate of feed of oil to the spinning ring will be properly maintained at all times regardless of the reservoir oil level or the rate at which oil is fed from the central source to the individual ring reservoir. If oil is fed to the reservoir at an excessive rate, the level is prevented from rising above a fixed point through the utilization of a dam at one side of the reservoir over which all surplus oil flows to escape into a drain which runs back to the main oil supply. In other words, the only requirement of the central oil supply system is to supply oil in sufficient quantity to maintain each individual ring reservoir full or at least partially full. With this accomplished, the wick arrangement running from the reservoir to the felts and from the felts to the ring controls the rate of oil delivery to the ring.

These and other objects of the invention will become more apparent as the description proceeds with the aid of the accompanying drawings in which

FIG. 1 is a plan view of a spinning ring and the associated holder (broken away in part), oil reservoir, felt compartment and drain compartment.

FIG. 2 is a vertical section taken on the line 2—2 of FIG. 1 to enlarged scale.

FIG. 3 is a plan view showing the reservoir, felts and drain in more detail, the cover having been removed.

FIG. 4 is a section taken on the line 4—4 of FIG. 1.

FIG. 5 is a vertical section similar to FIG. 2 showing a modified type of construction.

Referring to FIG. 1, there is shown therein a vertical type spinning ring 2 mounted in a holder 4 which is adapted to rest on a conventional ring rail. It will be understood that a large number of identical spinning rings and holders are positioned in side-by-side relation on the ring rail of the spinning frame. However, all of the rings and holders are identical, and therefore an explanation with respect to one unit will suffice for all.

At one side of the holder is a lubrication unit generally indicated at 8. This unit is preferably positioned at the rear of the ring rail to make connection with the oil feed pipe which extends therealong and supplies all of the rings. This portion 8 of the holder has three individual compartments, a felt compartment 10 in which are positioned the metering felts 12, an oil reservoir compartment 14 and an overflow and drain compartment 16. The three compartments are jointly covered by a transparent cover 17 secured by suitable pins 19 in a recess 21. Oil is supplied to the oil reservoir compartment by a common oil feed pipe 18 from which extends a branch line 20 leading through a port 22 high up in the outer wall 24. Between felt compartment 10 and reservoir 14 is a relatively high wall 26 notched along its upper surface as at 28. Two felts, in the preferred form, are placed one on top of the other at 30 and 32. Between these two felts reside the ends 34 of a wick 36 which extends up and over the wall 26, resting in the notch 28. The wick then drops down into the oil reservoir 14, with its ends 38 resting on the bottom thereof as indicated in FIG. 2.

At the other end of the oil reservoir is a relatively low wall or dam 40 separating the oil reservoir from the overflow compartment 16. A drain 42 leads from the overflow compartment to any suitable oil collecting tank.

As oil is supplied to the reservoir 14 through the oil supply pipe 18, it is obvious that as soon as the oil has risen to the level 44 any further oil supplied will flow over the wall 40 into the drain compartment 16 and out

the drain pipe 42. Thus the oil in oil reservoir 14 can never rise above the level 44 regardless of the rate at which it may be supplied by the common supply pipe 18.

Referring now to FIGS. 1 and 2, it will be seen that at the lefthand end of the metering felts 12, a wick 46 is positioned therebetween which leads in the usual manner through a passage 48 to the spinning ring 2. As shown in FIG. 4, the ring 2 has thereabout its outer circumference a groove 50 in which resides the wick 46. Thus oil in the felts 30 and 32 is transferred by capillary attraction to wick 46 which carries it about the ring 2 to be absorbed by the porous metal to distribute itself all over the ring surface and thereby to lubricate the traveler 52 as it moves about the ring.

In this way, regardless of the rate that oil is fed through the common supply pipe 18, the oil can travel to the ring only as fast as it is conveyed by wick 36 to the felts and thence by wick 46 to the ring. This eliminates the necessity for any accurate control of the pumping mechanism from the common supply that forces oil through pipe 18. The control of the rate of feed remains with the felts.

A modification of the invention is shown in FIG. 5. This is a vertical cross-section taken through the lubrication unit and is generally similar to FIG. 2. In this construction, the oil reservoir is indicated at 54. The oil is supplied through pipe 56 which is connected with the common oil source. A relatively low wall 58 is at the other end of the oil reservoir adjacent which is the overflow or drain compartment 60 from which leads the drain pipe 62 by which oil may return to a storage tank for re-use.

The felt compartment 64 comprises a supporting floor 66 carried by a plurality of bosses 68. This compartment, instead of being alongside the oil reservoir as shown in FIGS. 1 to 4, is located above the maximum level of oil in reservoir 54. Two felts 70 and 72 are carried by floor 66 and are covered by the transparent cover 74. The maximum level that the oil can reach is indicated by the line 76. The oil is conveyed from the oil reservoir to the felts 70 and 72 by a wick 78, the upper end of which at 80 is shown positioned between the lower felt 70 and the felt supporting floor 66. The wick 82, which is similar to wick 46, is positioned between the two felts 70 and 72 and transmits the oil from the felts to the spinning ring 2 in the same manner as previously described with regard to wick 46.

It is my intention to cover all changes and modifications of the examples of the invention herein chosen for purposes of the disclosure which do not constitute departures from the spirit and scope of the invention.

I claim:

1. Means for supplying oil to a powdered metal spinning ring, said means comprising an oil reservoir, means for supplying oil to said oil reservoir from a central source, overflow means associated with said reservoir to limit the quantity of oil that may be retained in said reservoir, a compartment adjacent said oil reservoir, metering felts in said compartment, a first wick leading from said oil reservoir above the oil level thereof over a separating wall and into contact with said metering felts, and a second wick spaced from said first wick and leading from said felts to said powdered metal spinning ring whereby regardless of the rate at which oil may be fed to said reservoir the rate of oil fed to said ring will remain under the control of the wicks and the metering felts.

2. Means for lubricating a porous metal spinning ring,

said means comprising piping leading from a central oil supply, an oil reservoir, a compartment containing metering felts adjacent said reservoir, said reservoir and compartment separated by a relatively high wall, said reservoir having a wall lower than said high wall at one side thereof for limiting the height to which oil can rise in said reservoir to a level which is below the top of the wall between said reservoir and felt compartment, a drain adjacent said lower wall thereby oil overflowing said lower wall may escape through said drain, a wick having one end in said reservoir and leading up and over said higher wall into said felt compartment where it is in contact with said felts to transmit oil by capillary attraction from said reservoir to said felts, and another wick extending from said felts to said spinning ring.

3. In combination with a spinning ring holder, oil supplying means for a spinning ring carried by said holder, said oil supplying means comprising a lateral extension of said holder and having walls therein forming three compartments, the first compartment containing metering felts, the second compartment being an oil reservoir with a low wall at one end and the third compartment acting as an overflow compartment to receive oil overflowing said wall from said second compartment, the wall between said metering felts compartment and said oil reservoir extending horizontally and above the maximum oil level in said reservoir as determined by said low wall, a wick extending from said reservoir to said felts, a piping system for supplying oil to said reservoir, and a drain from said overflow compartment to drain off oil that may flow into said overflow compartment from said oil reservoir.

4. In combination with a spinning ring holder, oil supplying means for a spinning ring carried by said holder, said oil supplying means comprising a lateral extension of said holder and having walls therein forming three compartments, the first compartment containing metering felts, the second compartment being an oil reservoir and the third compartment acting as an overflow compartment to receive oil overflowing from said second compartment, the wall between said metering felts compartment and said oil reservoir being higher than the wall between said oil reservoir and said overflow compartment, a wick extending from said reservoir to said felts, a piping system for supplying oil to said reservoir, and a drain from said overflow compartment to drain off oil that may flow into said overflow compartment from said oil reservoir.

5. Means for supplying oil to a powdered metal spinning ring, said means comprising an oil reservoir, means for supplying oil to said oil reservoir from a central source, overflow means associated with said reservoir to limit the quantity of oil that may be retained in said reservoir, a compartment adjacent said oil reservoir, metering felts in said compartment, a first wick leading from said oil reservoir above the oil level thereof and into contact with said metering felts, and a second wick spaced from said first wick and leading from said felts to said powdered metal spinning ring whereby regardless of the rate at which oil may be fed to said ring will remain under the control of the wicks and the metering felts.
